(57) **CLAIM**

The ornamental design for a bag with an attachment, as shown and described.

DESCRIPTION

FIG. 1 is a top, right, front perspective view of a bag with an attachment;

FIG. 2 is bottom, right, front perspective view thereof;

FIG. 3 is a top, left, back perspective view thereof;

FIG. 4 is a front view thereof;

FIG. 5 is a left view thereof;

FIG. 6 is a right view thereof;

FIG. 7 is a top view thereof; and

FIG. 8 is a top view thereof;

FIG. 9 is a top, right, front perspective view of a bag with an attachment from FIG. 1, where the bag attachment carries a hat on the side of the bag;

FIG. 10 is bottom, right, front perspective view thereof;

FIG. 11 is a top, left, back perspective view thereof;

FIG. 12 is a front view thereof;

FIG. 13 is a left view thereof;

FIG. 14 is a right view thereof;

FIG. 15 is a top view; and,

FIG. 16 is a top view thereof.

The dashed and dotted broken lines in the drawings depict portions of the article that form no part of the claimed design. The dashed broken lines showing a hat in FIGS. 9, 10, and 12-16 depict environmental subject matter that forms no part of the claimed design.

1 Claim, 16 Drawing Sheets
